UNITED STATES PATENT OFFICE.

ALBERT RITSEMA, OF WICHERT, ILLINOIS.

COAL-SIFTER.

1,324,067.

Specification of Letters Patent.

Patented Dec. 9, 1919.

Application filed May 27, 1918. Serial No. 236,794.

To all whom it may concern:

Be it known that I, ALBERT RITSEMA, a citizen of the United States, residing at Wicher, in the county of Kankakee, State 5 of Illinois, have invented certain new and useful Improvements in Coal-Sifters; and I do hereby declare the following to be a full, clear, and exact description of the invention, such as will enable others skilled in the art 10 to which is appertains to make and use the same.

The present invention relates to new and useful improvements in sifting devices, more particularly of that type intended for sift- 15

ing ashes. It is the object of the present invention to provide a device of maximum simplicity wherein the dust incidental to the sifting operation is confined to afford a comparatively 20 comfortable and clean sifting operation, this simplification of structure being procurable by the provision of a dust confining means carried by and reciprocable with the sieve.

It is further an object to provide an arrangement wherein a sieve may be associated with or detached from a dust confining means of the present nature in a most ready manner to facilitate loading and unloading of the sieve between the sifting operations. 25

A still further object resides in the provision of an arrangement for dampening the dust and ashes discharged from the sieve in the sifting operation.

With the above and other objects and advantages in view, the invention resides more particularly in the novel combination, formation, and arrangement of parts hereinafter described and particularly pointed out in the appended claim.

40 In the accompanying drawings:

Figure 1 is a perspective view of a sifting device constructed in accordance with the present invention.

Fig. 2 is a vertical sectional view there- 45 through on the line 2—2 of Fig. 1.

Fig. 3 is a plan view of the device with the cover removed.

Fig. 4 is a sectional view taken longitudinally through the device.

50 Fig. 5 is a detail perspective view of one of the water distributing apertures and the shield therefor.

Referring now more particularly to the accompanying drawings, there is provided a 55 sieve comprising an imperforate and preferably wooden wall frame 5 of rectangular

shape and carrying a screen bottom 6, a handle 7 projecting outwardly from the central portion of one end of the frame. This frame is adapted to fit within the upper portion 60 of a casing constructed of relatively light metal and comprising side walls 8, end walls 9, bottom 10 and a cover 11 secured by hinges 12 at one side edge to an edge of the upper edge of a wall 8. The walls of the casing 65 are provided with inwardly projecting seating blocks 15 at the corners of the casing adapted to support the sieve frame substantially flush with the top of the casing, and the handle 7 of the sieve projects through 70 a slot 16 in the upper portion of one end wall 9 which slot is open at the upper edge of the wall.

Thus the sieve may be readily secured within the casing, or removed therefrom, 75 and in secured relation it is noted that the sieve and casing are held against any relative movement and thus the casing may be shaken or reciprocated with the sieve in the usual manner by an operator gripping the 80 sieve handle 7. A maximum freedom of shaking action for the sieve is thus afforded and a maximum simplicity of structure is attained in the provision of a means for confining the dust of the sifting operation, 85 while the casing by reason of its light nature does not interfere materially with or add to the labor of sifting.

In the present structure an ash pan 17 is 90 slideable in the bottom of the casing, and is removable through an opening 18 in the end wall 9 through which the sieve handle 7 projects, this pan being normally secured within the casing by a clip plate 19 pivoted on the outer face of the wall 9 and engageable with its outer wall. Thus the casing 95 may be emptied of ashes without the necessity of tilting the same. For sprinkling the ashes as they are shaken from the sifter and thus lessening the amount of dust within the 100 casing, a pair of elongated cylindrical water reservoirs 20 are secured to the inner face of the side casing walls 8 in the space between the bottom of the sifter and the top of the ash pan by suitable strips 21 em- 105 bracing said cylinders and riveted to the casing walls. These cylinders are provided with filling nipples 22 at their central portions which extend outwardly of the casing, and are each provided at their inner sides 110 with water discharge apertures 23 through which water is splashed into the ash pan

space by the jarring incident to the sifting operation. Cupped shield plates 24 are secured to the reservoirs immediately above these openings and serve to prevent clogging of said openings by ashes dropped from the sieve, and also assist in spreading the water as it is splashed from the apertures.

While the structure shown and described forms one preferred form of my invention it will be appreciated that various changes and modifications of structure may be resorted to or various features added or eliminated without departing in any manner from the spirit of the present invention as defined by the accompanying claim.

What is claimed is:

A sifter including a casing, a sieve removably disposed in the casing in a way to be

held against movement with respect to the casing during a sifting operation and for movement of the casing therewith during such operation, and water containers mounted in the casing longitudinally of the direction of motion of the casing during a sifting operation and having splash openings at their ends for the egress of water from the containers to the casing as a result of surging of water in the containers incident to reciprocation of the casing.

In testimony whereof, I affix my signature, in the presence of two witnesses.

ALBERT RITSEMA.
